UNITED STATES PATENT OFFICE.

JOHN MARSHALL VANNEMAN, OF PHILADELPHIA, PENNSYLVANIA.

GARMENT

1,092,677.

Specification of Letters Patent.

Patented Apr. 7, 1914.

Application filed August 29, 1913. Serial No. 787,370.

To all whom it may concern:

Be it known that I, JOHN MARSHALL VANNEMAN, a citizen of the United States, residing at Philadelphia, in the county of Philadelphia and State of Pennsylvania, have invented certain new and useful Improvements in Garments; and I do hereby declare the following to be a full, clear, and exact description of the invention, such as will enable others skilled in the art to which it appertains to make and use the same.

This invention relates to garments and has for an object to provide a garment having means for attaching and supporting the catamenial bandage.

A further object of the invention is to provide an elastic garment on both its anterior and posterior parts with an internal reinforce and an external loop through which the ends of a catamenial bandage may be inserted and secured in any approved manner.

With these and other objects in view the invention comprises certain novel constructions, combinations and arrangement of parts as will be hereinafter more fully described and claimed.

In the drawings: Figure 1 is a view of a figure showing the front of a garment with the bandage attached. Fig. 2 is a rear view of a figure with the bandage attached. Fig. 3 is a perspective detail showing the manner of attaching the loop to the garment.

Like characters of reference designate corresponding parts throughout the several views.

The garment to which the article which forms the subject matter of this application is attached is disclosed in the drawing as a union or combination suit but it is to be understood that the invention is not limited to such union or combination garment of an elastic nature but to any garment arranged with the supporting means hereinafter described. The supporting means comprises a loop 10 in front and a similar loop 11 at the back, each being secured at its ends to the garment with the central portion of the loop

rather full and so positioned that a bandage 12 may be inserted between the loop and the exterior of the garment and secured in any usual and approved manner, as by a pin.

The loop may be secured to the garment in any manner found adaptable but for reinforcing and strengthening it is found desirable to attach a tape 13 to the inner surface of the garment by a row of stitching 14 entirely around such tape 13 with other stitches 15 for securing the loop 10 in position, such stitches passing through the garment fabric and through the tape 13 whereby the stress exerted upon the loop 10 is carried by the tape 13 as distinguished from being carried directly by the stitching of the ends of such loop to the garment fabric. The latter, being an undergarment such as a union suit as shown, is usually of elastic or Jersey cloth and would draw out of shape if the strain were thrown upon it direct. By this means the loop 10 is secured in such manner as not to be easily broken away from the garment and yet to provide ample and sufficient means for supporting the bandage.

The use and operation of the device will be clearly and fully understood from the foregoing description and reference to the drawing.

I claim:

The combination with an elastic undergarment: of a horizontal tape inside the same at the front near the waist line, a row of stitching through the garment and tape around the edge of the latter, a loop overlying the tape outside the garment, stitches through the garment and tape and through the ends of the loop, the latter being full and loose when the tape is taut, and a similar loop and tape at the rear of the garment, as and for the purpose set forth.

In testimony whereof I affix my signature in presence of two witnesses.

JOHN MARSHALL VANNEMAN.
